(57) **CLAIM**

We claim, the ornamental design for a portable carrier, as shown and described.

DESCRIPTION

FIG. 1 is a front perspective view of a portable carrier, showing a first embodiment of our new design in a first configuration;

FIG. 2 is a front perspective view of a portable carrier, showing the first embodiment of our new design in a second configuration;

FIG. 3 is a front elevation view of the portable carrier of FIG. 2;

FIG. 4 is a top view of the portable carrier of FIG. 3;

FIG. 5 is a side elevation view of the portable carrier of FIG. 3, wherein both side views of the first embodiment are mirror images of each other;

FIG. 6 is a bottom view of the portable carrier of FIG. 3;

FIG. 7 is a rear elevation view of the portable carrier of FIG. 3;

FIG. 8 is a front perspective view of a portable carrier, showing a second embodiment of our new design in a first configuration;

FIG. 9 is a front perspective view of a portable carrier, showing the second embodiment of our new design in a second configuration;

FIG. 10 is a front elevation view of the portable carrier of FIG. 9;

FIG. 11 is a top view of the portable carrier of FIG. 10;

FIG. 12 is a side elevation view of the portable carrier of FIG. 10, wherein both side views of the second embodiment are mirror images of each other;

FIG. 13 is a bottom view of the portable carrier of FIG. 10;

FIG. 14 is a rear elevation view of the portable carrier of FIG. 10;

FIG. 15 is a front perspective view of a portable carrier, showing a third embodiment of our new design in a first configuration;

FIG. 16 is a front perspective view of a portable carrier, showing the third embodiment of our new design in a second configuration;

FIG. 17 is a front elevation view of the portable carrier of FIG. 16;

FIG. 18 is a top view of the portable carrier of FIG. 17;

FIG. 19 is a side elevation view of the portable carrier of FIG. 17, wherein both side views of the third embodiment are mirror images of each other;

FIG. 20 is a bottom view of the portable carrier of FIG. 17; and,

FIG. 21 is a rear elevation view of the portable carrier of FIG. 17.
